(57) **CLAIM**

The ornamental design for a display screen or a portion thereof with animated graphical user interface as shown and described.

DESCRIPTION

1. Display screen or portion thereof with animated graphical user interface

2. Display screen or portion thereof with animated graphical user interface

3. Display screen or portion thereof with animated graphical user interface

1.1 : Front

1.2 : Front

1.3 : Front

2.1 : Front

2.2 : Front

2.3 : Front

2.4 : Front

3.1 : Front

3.2 : Front

3.3 : Front

3.4 : Front

The appearance of the animated image sequentially transitions between the images shown in reproductions 1.1 to 1.4, 2.1 to 2.4, and 3.1 to 3.4. The process or period in which one image transitions to another image forms no part of the claimed design. The broken line rectangle and the broken "X" illustrate the display screen or portion thereof and form

(Continued)

no part of the claimed designs, whereas all other broken lines show a part of the claimed designs.

1 Claim, 12 Drawing Sheets
